The Schedule is加入 to in this Letter Patent and making part of the same containing a description in the words of the said James Thompson himself of his improvement in the mode of opening and shutting switches upon Rail Roads.

To all whom these Presents shall come

Be it known that I James Thompson of the City and County of Baltimore and state of Maryland have invented a new and useful improvement in the mode of opening and shutting switches upon Rail Roads which improvement consists in providing the means whereby the Drivers of cars or any kind of Carriages upon rail roads, or the Superintendents of Locomotive Engines, can open and shut the switches to enable them to crop from one track to another, so they, please without stopping or leaving their seats or stations, or requiring the assistance of any one else upon the road; and that the following is a full and exact description of the said invention or improvement, as invented or improved by me viz, I will first describe the switch in common use, that a better understanding of the improvement may be had; said switch is formed in shape like a wedge, it is of iron four feet in length, more or less, three inches wide at the heel, where it is rounded horizontally about said end, tapering down to about a quarter of an inch more or less, at the opposite end, and is about one and $\frac{1}{2}$ eight of an inch deep or less its whole length; the switch has a pin of considerable size, say one and a quarter of an inch diameter, more or less, fast into the heel or near the rounded end, said pin passes down through a slate of cast or other iron, which plate is the track rail upon which the rail road carriage wheels travel; the back pin passes through said plate or rail, and has a bay through it to prevent its being displaced. A part of my invention or improvement is to make a square or flat tenon upon the lower end of said pin, a little flush of the outer side of the iron plate through which it passes, hence its whole length out having square shoulders at the termination of the rounded part, and a bay hole through it near the bottom. I also purpose to form a piece of iron similar to the above switch one way, but quite thin the other, at the wide end of which, a square or

flat hole, should be made conformable to the shape of the bar on the aforesaid pin, which iron should be made to fit tight and strong upon said tongs, and the bar through said pin under the last mentioned, were, should be drawn in, forcing said iron tight up to the shoulders, in which situation said iron should lay, under the rail or plate parallel with the switch above it and fasten to more easily under said plate or rail; said iron may be of the same length of the switch moreover, and should have a short round tenon at the small end, which end is opposite to the heel pin; said iron thus connected to said pin, which is fast in the heel of the switch. I will call the switch Lever; The said switch Lever, is thus fastened to the heel pin of the switch, for the purpose of opening and shutting it, and it being under the iron plate on which the wheels of the carriage run, no harm can reach it, whether stones, gravel, water or ice, of properly received by a being placed each side and below the iron plate or rail. The next article I purpose, is, that for opening and shutting the switches, by a connection between it and the carriages, and which may be effected, in the following manner or mode, or any other way which may be preferred. First then; a wood or stone post may be fixed solid in the earth, between the tracks, or connected or fastened to the track rails, or sleepers preferring the last mode as it would be exempt from injury by frost, at such a distance from the track rails as shall be most convenient; with said post in the ground or on the rails may be connected an upright iron shaft; its top should reach a little above the post with a gudgeon near the top and bottom, confined in boxes or cleats, so that it can turn round or vibrate one way or the other; at the lower end should be fixed a shank or arm on the end of the upright post or shaft, or it may be cut out straight at right angles with the upright, six inches, more or less, in length; and a steel pin should be made fast projecting upward in said shank at a proper distance from the centre of the upright, to gain by a small motion of the upright sufficient movement, to open or shut the switch, which movement of the switch, is only about two inches; there must be connected to the steel pin in the shank or arm of said upright, and of iron; the opposite end to that on the steel pin should be connected to or slipped upon the round tenon on the end of the switch lever having a pin outside of it through the tenon to prevent the connecting rod from getting off; said connecting rods should be of sufficient

cient strength to open and shut the switch by pushing, or pulling, which will be alternately the movement necessary made to open and shut said switch, there should be fastened immovably upon the top of the upright, shaft a rhombus, parallelogram, or diamond shaped iron lever made of iron one inch thick, more or less, by inches wide, more or less, in the centre, terminating in a point at each end, a shaft passing through or into it, as near one point as may be with safety; said iron at its widest part should be only so wide that when any iron article or substance passes within its point at the upright on a line with the track rails, of the road, that it will cause said diamond shaped iron to move or swing out, so far as to clear the switch so that the carriage can pass said switch without entering it: or should it have been the desire of the Driver to have made a crossing, he should when approaching it, have changed the article attached to his car, so that it should have passed upon the outside of the upright shaft and come in contact with the outer edge of the diamond shaped iron iron; which being so wide in the middle, that before the iron attached to the carriage thus moving along its side, could pass said middle, it would have opened said switch, in which case the car would have crossed to the other track. The said iron fixed upon the top of the upright, vibrating shaft, should be in shape similar to a long narrow diamond, pointed at both ends, that is, at the end where the shaft goes through and the opposite, so that in returning through said crossing, the iron which is fixed upon the carriage to move or vibrate said diamond with, shall not catch against it, but by its having a point the said iron can better made to pass it upon either side at the pleasure of the driver. The said diamond or rhombus shaped iron lever, will cover the top of part to which the upright is connected and lay horizontally above its top, the diamond shaped iron may be open in its centre, having a rim only all round of sufficient strength, which opening will enable me to cover the top, of each post and vibrating iron, with a cap of iron, or any thing else, extending each way beyond the post to protect it from harm or weather. The iron shaft should also be cast about, and a trunk be extended from it to the switch lever under ground, to protect the connecting iron from all harm, or impediment to its movement. The regulating rod, if any, in the carriage, may be of round iron fixed to vibrate in journals extending up from the bottom of the side rails of the carriage to the Driver, having a han-

be upon the top standing out right angles to the upright rods; to turn it with and there may be two notches to lay said handles into, that when in the inner notch, it shall cause all the switches which may be placed to close, and when put into the outer notch, it will cause them to open; so that should the driver wish not to open at all he places the handle in the inner notch; and should all the switches be open when he meets them, they will all close before the wheels come in range with them; and thus he can open or not without leaving his seat or horse. The bottom end of said regulating iron, must be bent out from the upright part just below the bottom edge of the side rails at right angles, sufficient to pass either side of the cap over the posts, as before described, then bent down sufficient to reach at a proper distance below the cap, then again at right angles towards the upright; until it approaches so near that it will reach the vibrating iron upon the upright iron shaft under the cap, but not within three or four inches, more or less, of the upright, which is the centre of its own motion, and then the end may be spread as wide as the edge of the vibrating diamond shaped iron or wider, and rounded so as to slide easily along the edge, or it may be again bent down, or up, as thought best, in view of spreading it at the end. Thus the iron regulator, will represent a crank with a return shank shorter than the other upon which it revolves by three or four inches more or less, now it may be understood, or seen, that if the driver turns this crank out, it will pass outside of the upright iron shaft, which is the centre of motion to the diamond shaped lever or wiper, this will cause the vibrating lever or wiper, under the cap to move out, which motion will open the switch; which is effected by the driver, by the aforesaid handle upon the top of the upright rods, which is the centre of motion to the crank, or if he turns the crank in, it will pass inside of it which will move the vibrating lever the other way and thereby close the switch; provided the centre of the crank motion on the carriage passes directly over the upright shaft, which is the centre on which the upright is hinged, and as the centre of one upright must necessarily pass over that of the other, it will of itself be a sufficient guide for fixing their most convenient station. In stead of the upright shaft upon the post between the tracks to open the switches with, an iron centre a little above its middle upon a fast post in each post, and near to its inner edge may be substituted; and about a foot

can be acted upon by a spring to shut the switches with, I will call it a spring pendulum, or if it should ^{be made} to act by gravity, I will then call it a pendulum weight lever, the before described connecting rods between the switch lever and the upright shaft should in this case be contraried upon a fast pin, three inches, more or less, below the centre of said spring or pendulum weight lever, the top or upper end of said pendulum when the switch is closed, should rather lean towards said switch, it may be mounted at top and have a roller or pulley, placed at a proper distance above the centre on which it is to vibrate, or not as desired; said roller or pulley is designed to ~~accordance~~ for the movements connected with the carriages to act upon while opening the switches to save friction, if said pendulum should be used as a weight pendulum or lever it may be formed like the latter ~~is inverted~~ thus: I turned in towards the switch with sufficient weight, to move to close the switch by its own gravity with safety, To move said spring or pendulum weight lever, so as to cause the switches to open, a board or other material six inches wide, more or less, attached to and suspended by hinges or joints to the top and outside edge of the bottom and outer rails of the carriages or both sides cylindring a little beyond said rails at each end, and bevelled off to a long and easy slant from the edge on which it is centred outwards, and this outer edge of said board, may be covered with thin steel iron ground smooth, and said board when not in use, may hang perpendicular by the outside of the rails, A stiff fence of iron or other metal considerably out of square, may be fastened upon each end of said board, so as to move just free of the ends of the rails, one end of the fence projecting three or four inches, more or less from the upper edges of said boards, To the outer end of said fences should be centre connected rods cylindring in to the centre of the carriage, or to either side side of the centre if more convenient, and there connected with the upright which leads to the neck of the Driver, said upright should have arms fast upon its lower end cylindring each way from its centre, five inches, more or less, at the outer ends of which arms, said pins should be fixed fast, on which the connecting rods are to stay. The upright having a handle or a wheel to turn said upright with, the upright being confined in top and bottom just so as to move easy when the Driver should desire to make a crossing from one track to the other, it will be necessary for him to turn round the wheel or handle of

the upright sufficiently to raise the boards situated on each side of the carriage, in horizontal line, in which position as he passes the spring or pendulum lever, the outer edges of said boards should come in contact with the roller or pulley upon the top end of said pendulum, and cause the top end of said pendulum lever to move out and thereby open the switch. said boards extending the whole length of the carriage, the switch will be kept open until after the hind wheels shall have entered said switch, and as soon as the boards shall have passed the pendulum lever, the switch will immediately reclose, in which position it would be most desirable it should continue, as in that position, it would keep out stones, dirt, ice, or snow; and when the switch was forced open all those articles of obstruction if about would slip into the path before it, and thus leave it free to return again to its former place, if the switch was generally left open all the aforesaid articles might accumulate within in it, and thus would necessarily have to be removed by the attention of some person before the switch could be closed. If the carriages are not turned about at each end of the line, it will be necessary to have the uprights and switch at each end and the same in the first mentioned case or operation. The post to which the pendulum is connected may be cased and covered to enclose all the iron about it except in the range of the top end of the pendulum lever, where the boards or other fixtures attached to the carriage, pass in the range of which, a notch should be cut into the post and casings under the cap, to be of sufficient depth to allow said boards to produce all the necessary movement upon said pendulum, and yet allow the cap above to screen it from any injury from the weather &c. It should as before described, in all cases leading from the post under ground to the switch, will found the connecting rods be used therefor should not be omitted. The uprights first described connected to the carriage may be only of sufficient length from the crankup to reach just above the top of the carriage rails to which they are fastened. The top end bent out at right angles, may be six inches long, more or less, and serve as a wheel to turn it with, with a true pin fast in the outer end, on which to center a iron rod, said rod to extend thence into the centre of the carriage, or as near it as may be found convenient: the said connecting rod is to be connected on its inner end to the upright which reaches to the Driver, and in all respects be as described in the other case, and if the carriage should not always travel one end first, it will be necessary to have the aforesaid crank iron at the furthest end of the carriage.

ago, and two experts to operate them with as before set forth: or they may be fixed and formed in any other way or manner which may be preferred, or with any other materials &c. What I claim as my invention or improvement is the application of machinery to open and shut switches whereby the drivers of carriages or superintendents of Locomotive Engines or others, without stopping or leaving their seats in carriages or horses can open and shut switches if in error, by night or by day, without seeing them, by machinery as set forth in the above specification or in any other way, or manner.
